UNITED STATES PATENT OFFICE

JULIUS S. FOX, OF CLEVELAND, OHIO

AEROPLANE WING STRUCTURE

Original application filed March 5, 1926, Serial No. 92,424. Divided and this application filed December 30, 1926. Serial No. 157,924.

This invention is a division of the application, Serial Number 92,424, filed Mar. 5, 1926, for safety aeroplanes, from which claims to the wing structure were canceled by applicant responsive to office action of Sept. 17, 1926, and relates to aeroplane wing structures of the aeroplane type, though the principles herein disclosed may also be used in other forms of air ships, as in those of the dirigible type. My improvements have for their general purpose a more positive stability of structure and more certain equilibrium of the plane because of a lower position of the center of gravity of the machine relative to the sustaining planes and other lifting and supporting elements employed, it being a special purpose of my improved structural arrangement that the force of gravity shall always tend to hold the ship in equilibrium.

It is to be noted that the rather usual form of sustaining wings for both aeroplanes and dirigibles, when wings are employed, is a substantially straight-line form in the direction of their length, that is, in a line transverse of the fuselage of the machine. Or, if the design of the wing in this direction has not been followed, the tips of the wings have usually been bent downwardly by raising appreciably the center of the wing, which will, of course, raise rather than lower the center of gravity of the weight of the ship, and thereby tend to destroy the equilibrium thereof.

It is a special object of my invention that I have attained the desirable result of lowering the center of gravity of an air ship relative to the sustaining planes thereof, and on whatever form of air ship they may be used, without pluralizing the number of planes therein. Heretofore it has been my observation that even a slight lowering of the center of gravity in aeroplanes, has been accomplished by mounting the planes above the fuselage, usually in a plurality of spaced members, so that such lowering of the gravity center cannot be done with mono-planes, and in fact can hardly be done with biplanes. Hence the object of my improvements.

It is a further object of my invention that I have accomplished another valuable func-

tion other than the relative lowering of the gravity center with respect to the sustaining wings, which is associated also with the structure of the wings themselves—that of reforming the wing structure by curving the latter in the direction of its length, transverse of the ship. This effect desirably shapes the said wings by lowering the juncture of the two side wings of a pair used in a unitary plane, to a point far below the tips of these wings, this in itself serving a further purpose in stabilization of the ship, this resulting in fact in forming these wings in the general shape resembling the wings of birds, and thereby evidently serving the same purpose.

It is an object of my improved structure, therefore, to suspend the fuselage from the meeting point of the wings of a common pair, lowering this point of suspension by bending downward the junction line of such wings in a mono-plane, or by bending downward the centers of both pairs of transverse wings, when more than one pair is used, in a biplane the fuselage being mounted between the pairs of wings but somewhat below the longitudinal axis of the lower pair, and far below the upper pair of wings.

It is a further object of my novel improvements to provide hollow wings for one or more pairs used, and to amply brace said wings interiorly, so that the outer walls of the wings will be spaced, somewhat more at their transverse centers than at their tips, such space nearly disappearing at the very tips. This construction not only provides for strengthening the wing structure just where the "bend" occurs at the junction of the wings of each pair, but also provides for strong wings in spite of their being hollow, and therefore provides proper structure for making possible and practicable inflation thereof by a lighter-than-air gas which it is my further purpose to use on my improved air ship.

The particular form and arrangement of my improvements will now be described in detail, recited in the appended claims and illustrated in the accompanying drawings, in which—

Figure 1 is a front elevation of a biplane embodying therein my improvements;

- Figure 2 is a plan view of the same;
 Figure 3 is a side elevation of a biplane, certain parts being shown in transverse section;
 Figure 4 is a plan view of an end only of the upper wing of an aeroplane, certain cross brace structures being shown in dotted lines;
 Figure 5 is a view of the tip of an upper wing, showing the vane in a bent position;
 Figure 6 is a perspective view of the truss frame of a portion of a wing;
 Figure 7 is a cross section of a lower wing, as taken on the line 7-7 of Fig. 1; a portion of the covering being turned back;
 Figure 8 is a perspective view of a cross brace frame for the spaced trusses of a wing;
 Figure 9 is an end view of the same; Figs. 6 to 9 are shown on a larger scale, and
 Figure 10 is a detail view in perspective 20 of a cross brace for a truss.
 My improved wing structure is shown in Fig. 1 as embodied in a biplane normally mounted upon a frame 5 for landing purposes, with usual front wheels 6, fuselage 7, and forward propeller 8. The upper pair of wings 9 shows in this view the characteristic edge form thereof, this latter showing the general longitudinal downward bending of the same at their junction 10 which has the function of lowering the point of support of the fuselage 7 therebelow, as will be more particularly explained in subsequent paragraphs. This junction point of the planes is not a single transverse line across the plane, but comprises an independent arc 11 extending across the plane at its center, and joining both wings of this pair respectively along lines 12, the inner ends of the wings curving downward from the straight portions 13, on the arcs 14, as shown clearly in this view.
 These wings 9 are attached to the fuselage by the posts 15 and braced against lateral and vertical strains by the diagonal cables 16. A very important feature of this wing structure lies in the mounting of the vanes 17 upon the rear portion of the tips of each, in hinged relation to the parts 13 in the same manner as they may be pivoted to the said parts of the planes of a mono-plane, and as shown in Fig. 2 in plan view. The mounting of these vanes 17 upon the planes of any aeroplane structure, makes it feasible that the vanes 17 may be actuated from the fuselage by cables or wires that are strung over suitable fulcra on the wings in pairs and attached at their ends to suitable portions of the vanes, so that pulling strains on the wires selectively will determine the direction the vanes will swing on the diagonal pivots 18.
 The particular detailed arrangement of the actuating wires and levers for controlling the vanes 17 become rather conventional for the purpose of raising or lowering such vanes on substantially horizontal hinges, but it is a 65 novel arrangement of these wires for control-
 ling the vanes of either side of the machine which I have provided, which consists in so relating the wires of opposite sides, that neither vane 17 of one side can be raised above the plane of the wing to which it is pivoted, without correspondingly lowering the vane on the other or opposite wing. Fig. 1 illustrates this relative position of the two vanes 17, whereby moving one of the vanes necessarily moves the other correspondingly, but in the opposite direction. This inevitably results in concerted action of the wings and vanes when tipping of the machine is intended as when curved flight is desired, and as will be explained more fully later.
 The fuselage 7 is suspended exceedingly low from the curved arc 11 of the plane surface of the aeroplane, and a consequent condition of stability results which has great advantages in certain conditions of flying, but which may make positive control of the machine, because of such lower center of gravity, somewhat difficult unless counteracted by the very certain related movement of the vanes as above described. It is especially desirable to move the vanes of a common pair of planes by a common actuating member, so that the machine is rendered quite stable because of the relatively low position of the center of gravity, and the pilot 10, by actuating the vanes 17 as above stated, may swing the machine either to the right or left as desired.
 The same general principle of stability and control is quite as feasible in multiplanes as in mono-planes, though I have shown the adaptation of the structure before explained, to a biplane, where the upper pair of wings is marked 19 and the lower planes 20 are provided with concave curves 24, which are equivalent to the curve portion 11 of the upper pair, and are joined by the junction lines 22 and straight portions 23, being like the junction line and straight portions 12 and 13 of the upper plane. The lower planes are not usually provided with vanes 17.
 The usual spaced supports 25 for biplanes are shown together with the usual cables 26, and in the showing here I have provided independent engines and propellers 21 which are supported upon the lower plane 20, spaced laterally of the fuselage 7 and rearwardly of the main propeller 8. The forward edges of the several planes are arranged out of alignment, the tips 27 of the planes being positively advanced forwardly of the central portion at the meeting points of the curved arcs 14. The stabilization of the entire machine resulting from the position of the transverse plane of the extreme ends of the wings, being not rearward of the propelling or pulling force at the points 21, is very positive and perceptible, and I regard it as an improvement for which I ask patentable protection per se.
 It is a special purpose of my invention to 130

construct all the wings of my machine, whether of one or a plurality of planes, hollow, and to inflate these hollow wing structures as I shall explain in detail. It is understood that the broad attempt to inflate compartments or other portions of aeroplanes has already been made. It is also known to have been attempted to even fill certain planes with lighter-than-air gases for assisting in the buoyant properties of the ship. In all these attempts that have been made to my knowledge, however, the practical application of the plan has failed because of the arrangement, which was thought essential by the proposers of the plan, of a combination in every case, of an inflation of the fuselage with such gas chambers associated with wings or borne thereby, connected by some pipes or with tubes for inflating the wing chambers from the larger gas chamber in the fuselage.

This has been found highly impracticable. In fact, the combination of the wing chambers with an inflated major gas chamber in the fuselage, was attempted because the wing chambers were understood to leak, due to the cruising force of the wing frames upon the gas tanks therein, so rapidly that they were found to require constant inflation from other sources of gas—hence, the inflated fuselage with all its attendant disadvantages. I have overcome this impracticable construction by building my wing structures of very strong truss frames 28, formed of cross braces 29, spacing elongated edge bars 30, of the form which the curved wing is to assume in cross-section, and confine the gas in the several wings in flexible bags which are held in pockets bound by said truss frames. The details of the structure of these pockets will be described in a later paragraph.

The several cross trusses for such wing structure are each made up of lengthwise sections 31 which are very strongly connected together edgewise at 41 on the plane of the truss by plates 32 having wide ends 33 connected with integral narrow portions 34. These plates 32 have means of attachment to the ends of the assembled truss sections and to the bars 30. This positively holds the truss formation and the resulting wing formation to the particular outline and design desired. In Fig. 3, I have shown the wings of both the upper and lower planes in section, illustrating the truss formation, and in Fig. 6, I have shown such structure of two such trusses assembled in spaced relation, and on a larger scale than in the other views.

From the above-mentioned views it will be evident that the length of the trusses 28 represent the width of the wing at that position of the cross truss. These wings have a wider breadth at the center between the tips, which gradually narrows to the extreme ends to which the vanes 17 are pivoted, as above explained.

As shown in Fig. 6, these trusses are spaced in parallelism transverse of, and for substantially the length of the wings. For the reason stated in the immediately preceding paragraph the length of the several trusses varies with the particular position it assumes in the wing. The several trusses are connected together at their forward ends by an integral bar 35 secured fixedly to the several trusses where each truss is independently braced by a plate 36 attached to the bars 30, the rear ends of each truss being also braced by an approximately triangular plate 37 connected to the bars 30 in the same manner as are the plates 36.

The cross trusses 28 are further held in suitable spaced relation by trusses 38 which may be formed of parallel bars 39, which trusses 38 are extended through the several cross truss frames 28 by means of spaced plates 40 to hold the bars 39 in secure position. I propose to use a large number of these cross truss frames 28, the latter being shown in Fig. 6 on a very large scale. I may provide them about fifty inches apart throughout the major length of the wing in which they are used. In some cases, however, they may be spaced somewhat farther apart. In any case, and it is understood that I am not to be limited to the particular measurements mentioned herein for the mere purpose of illustration only, it will be evident that these wings will be rendered very strong for stabilizing the wings for rendering the latter very resistant to air currents moving in various directions, and to eddies formed by the shape of the frame structure moving in any particular direction.

In any case, the general form of these trussed wings will afford strong resistance against outer air pressure, so that crushing force exerted by gas bags therein will not injure the hollow wings. And, especially by the force of the trusses 38 by means of the plates 42, which are quite similar to the plates 32, the wings are braced against both lateral strains and twisting forces exerted exteriorly upon the planes.

Between the elongated cross truss frames 28 within the wing frames, I have provided further strengthening braces in the form of end braces only, which comprise forward short frames 43 extending from the bar 35 to the frames 38, and rear short frames 44 extending from the rear frame 38 to a point quite in alignment with the rear ends 45 of the cross trusses 28. Between these cross truss frames 28 and the frames 38 there results, therefore, a hollow space bounded by these four trusses, which is intended to receive therein, as a sort of pocket, a gas bag for inflation, which will add to the buoyancy of the entire structure, and will be described more in detail later. These so-called pockets are strengthened and thereby rendered fur-

ther suitable for receiving the gas bags, by the provision of a lining on the inner walls of the pocket, this lining 80 being of suitable material attached to the walls of the pocket to provide support for the bag.

The provision of the end or short frames 43 and 44 is especially useful, in that they brace the side edges of the wings—the points where especial bracing is most needed. The 10 edge bars of the various truss frames, as well as the several short frames 43 and 44, serve the further purpose of supports for the wing covers 47 which, as shown in these views, are metallic sheets, preferably some 15 aluminum alloy, which are very thin and of course are very light in weight. These sheets 47 are not essentially made of aluminum, and in some instances will be made of heavy canvas or other textile sheets water- 20 proofed as may be readily done. They are attached to these frames named, and the edges 48 of the upper and lower sheets are secured to the bars 35 by screws or bolts, providing a strong outer surface for the 25 wings, as well as affording great strength within. The wing shown in Fig. 7, is a lower wing and is, therefore, provided with seams 49 at the connection of the end edges of the covers 47, but since the upper wings 30 of a plane are provided with the vanes 17, the hollow formation of the wings extends 35 to the hinge 18 only.

Fig. 7 is shown as having a portion of the upper cover 47 partially detached from 35 the trusses and folded back disclosing further structure of the interior of the wing. Between the outside covers 47, and held in proper position in the pockets formed by the truss frames as above described, are located gas bags 50 of gas-tight material, and provided with a common filling pipe or tube 51 having branch pipes 52, one of each leading to the bag in a given pocket. These bags are seated loosely in the several pockets except as they are held therein by the walls of the pocket. This feature permits slight shifting of the bags in the pockets to accommodate slight crushing effect of the trusses due to undue outer force on the wings, as 50 well as enables the bags to be removed for any purpose. This main tube 51 leads from a compressed gas tank which is located in the fuselage and provided with a valve to control the passage of gas to the wing bags. 55 This compressed gas tank is kept in any portion of the fuselage without any attachment thereto, and may be removed at any time for refilling. A main tube 51 is usually provided for the bags of each wing of the 60 entire machine, though this is not regarded as strictly essential.

It is to be noted that the vanes 17, hereinbefore described, are mounted for providing an effective variation relative to the length 65 of the two wings of a pair. These conditions

together with the low suspension of the center of gravity from the wings results in a safety of manipulation and certainty of control which is not to my knowledge afforded by machines not so provided with these structural features.

Special note is also made of the cross sectional form of the wings which adds greatly to the effectiveness of safety flight with this structure. It is emphasized that the forward 75 end of the frame 28 which we may term the "nose" 58, is formed of upper and lower curves 59 and 60, respectively, which meet at the edge formed by the bar 35, the lower curve 60 making a larger angle with the horizontal plane passing through bar 35 than does the curve 59. The effect of this shape is to give a lifting function to the planes due to the forward movement of the planes 80 into the air which latter tends to raise the planes by pressure underneath the same.

Many details of construction may be slightly changed without varying the operating principles of the machine or modifying the resulting functions thereof which 85 applicant relies upon for his advantages from his improvements. For example, standards 76 may be extended upward above the upper plane, and stay wires 77 connected to the ends of these standards to brace the 90 wings at the points 78 by reason of the concavo-convex arcs 14.

Having now described the structure of my improved mechanism and the manner of its 95 operation, what I claim and desire to secure by Letters Patent of the United States, is—

1. In an aeroplane, hollow wings each comprising an outer sheet covering and an inner frame structure comprising a plurality of truss frames positioned transverse of the wing and spaced apart the length of the wing, shorter frame trusses positioned between pairs of the longer trusses and extending from the common lateral edges of the wing and from the common line of the ends of the trusses for a portion only of the breadth of the wing, thus forming a pocket in the wing bounded by a pair of the larger, main transverse trusses and the inner ends of the shorter truss frames therebetween, and a flexible gas bag positioned in said pocket.

2. In an aeroplane wing, a hollow frame structure including elongated frame members extending transverse of the wing and spaced apart to form pockets between said member, the sides of each pocket being formed of two said transverse frame members in parallelism and the ends of said cross trusses connected with the truss frames, such ends being further braced by short truss frames, having narrow ends whose tips are in alinement with the narrow ends of the full length truss frames and their broader ends forming in part the outline of said pockets, a lining material attached to the 125

inner walls of the pockets, an outer sheet of material to enclose the pocket, and a gas bag removably and loosely held within the said lining.

5 In witness whereof I have hereunto set my hand this 24th day of November, A. D. 1926.
